WITNESS:

E. C. Fisher,
INVENTOR
BY *Victor J. Evans.*
ATTORNEY

UNITED STATES PATENT OFFICE.

EDGAR CLINTON FISHER, OF HUNTINGTON, WEST VIRGINIA.

FIRE ALARM AND INDICATOR.

Application filed July 5, 1922. Serial No. 573,023.

To all whom it may concern:

Be it known that I, EDGAR C. FISHER, a citizen of the United States, residing at Huntington, in the county of Cabell and 5 State of West Virginia, have invented new and useful Improvements in Fire Alarms and Indicators, of which the following is a specification.

This invention relates to an electric fire 10 alarm and indicator, the general object of the invention being to provide means for causing an alarm to sound when a fire occurs and also to indicate the room or apartment in which the fire is located.

15 Another object of the invention is to provide solenoids for actuating the indicators and for closing the circuits to the alarm means when a fire occurs.

The invention also consists in certain 20 other features of construction and in the combination and arrangement of the several parts, to be hereinafter fully described, illustrated in the accompanying drawings and specifically pointed out in the appended 25 claim.

In describing my invention in detail, reference will be had to the accompanying drawings wherein like characters denote like or corresponding parts throughout the several views, and in which:—

Figure 1 is a sectional elevation of one of the solenoids and its associated parts.

Figure 2 is an enlarged view of one of the fusible circuit closers.

35 Fig. 3 is a sectional view on line 3—3 of Fig. 1.

In these views, 1 indicates an alarm, which is electrically connected with a battery 2, or other source of supply, and with a conductor 40 strip 3 which is located in a casing 4. A second strip 5 is also located in the casing and this strip is electrically connected with the battery. A series of contact points 6 are arranged in the casing and these points 45 are connected with the strip 5. A series of levers 7 are arranged in the casing, these levers being connected with the strip 3 and are pivotally supported upon the posts 8. These levers are so arranged that one of 50 their ends will contact with the points 6 under the action of gravity so as to complete the circuit between the battery and the alarm through the strips and contact points, thus causing the alarm to be actuated. 55 These levers are normally held in raised position by being engaged by the cores of

solenoids 9, mounted in the casing, the levers carrying insulated plates 10 which are engaged by the ends of the cores. Each core carries a rod 11 which passes through guiding slots 12 in the plates 13 and each rod is adapted to raise a plate 14 in front of a window in the casing so that a numeral or other character or symbol will appear through the window to indicate which room 60 or apartment is on fire. This plate 14 is normally held in lowered position by gravity or other means. A switch 16 is placed in each room, this switch consisting of a lever 17 which is pivoted to a support 65 18 and is electrically connected to its solenoid by the wire 19, said switch is normally held out of contact with the terminal 20 by means of an easily fusible hook shape member 21, the terminal being connected with 70 the battery 2' by the wire 22. A casing 23 encloses the parts of the switch and a wire mesh formed in the lower wall of the casing.

From the foregoing it will be seen that if a fire should occur in a room the heat 75 therefrom would melt the member 21, thus permitting the switch lever 17 to drop upon the terminal 20 so as to close the circuit to the solenoid and cause the same to attract its core, thus lifting the indicator plate and 80 at the same time permitting the lever 7 to drop upon the points 6 and close the circuit to the alarm. Thus the invention will not 85 only sound an alarm when a fire occurs but it will also indicate which room the fire is 90 in. As shown all the points 6 and the levers 7 will be electrically connected with the alarm and battery by the conductors 3 and 5 so that any lever coming in contact with its point will close the circuit to the alarm 95 and each switch 16 is electrically connected with a solenoid in the casing so that this solenoid will be energized when its switch is closed by the melting of the fusible member of the switch.

100 It is thought from the foregoing description that the advantages and novel features of my invention will be readily apparent.

I desire it to be understood that I may make changes in the construction and in 105 the combination and arrangement of the several parts, provided that such changes fall within the scope of the appended claim.

Having thus described my invention what I claim is:

110 An alarm of the character described comprising a casing, a plurality of parallel ar-

ranged posts rising from the bottom of the casing, a lever for each post and being pivotally secured thereto, a strip longitudinally disposed in said casing and being secured to one side wall thereof, a plurality of contact members secured to said strip and being arranged in the path of one end of the levers, an insulated plate arranged on one end of each lever, a solenoid for each

lever and being adapted to normally engage the insulated plates for holding the levers out of contact with the contact members of the strip, a second strip arranged in the circuit with the respective posts and means actuated by the solenoids for operating an indicator.

In testimony whereof I affix my signature.
EDGAR CLINTON FISHER.
